UNITED STATES PATENT OFFICE.

JOHN GEORGE ZIEGLER, OF READING, PENNSYLVANIA.

DESIGN FOR A BRAKE-RING FOR COASTER-BRAKES.

SPECIFICATION forming part of Design No. 33,788, dated December 25, 1900.

Application filed November 24, 1900. Serial No. 37,691. Term of patent 7 years.

To all whom it may concern:

Be it known that I, JOHN GEORGE ZIEGLER, a citizen of the United States of America, and a resident of Reading, in the county of Berks and State of Pennsylvania, have invented and produced a certain new and original Design for a Brake-Ring for Coaster-Brakes, of which the following is a specification.

Figure 1 is a side elevation, and Fig. 2 an inner face view, of a brake-ring, showing my design.

As shown in the drawings, the leading or material features of my design consist in the conformation of the plate *a* and of the hub *b* thereon, said plate having a flat annular por-

tion *c*, to the inner edge of which the hub is united, and a conical extension *d*, overhanging the hub and terminating in a rim *e*, and said hub *b* being cylindrical in form and internally screw threaded, as indicated at *f*. 20

What I claim is—

The design for a brake-ring for coaster-brakes, substantially as set forth.

Signed at Reading, Pennsylvania, this 20th day of November, 1900.

JOHN GEORGE ZIEGLER.
